SHORTS OR THE LIKE

Irving Smith Marks, New York, N. Y.

Application November 26, 1949, Serial No. 6,266

Term of patent 7 years

(Cl. D3—17)

To all whom it may concern:

Be it known that I, Irving Smith Marks, a citizen of the United States, residing in New York, county of New York and State of New York, have invented a new, original, and ornamental Design for Shorts or the like, of which the following is a specification, reference being had to the accompanying drawing, forming part thereof.

In the drawing:

Fig. 1 is a front view of a pair of shorts, showing my new design;

Fig. 2 is a side view thereof, on smaller scale, illustrated in wearing position;

Fig. 3 is a front view thereof; and

Fig. 4 is a rear view, on smaller scale, of the shorts shown in Fig. 1.

I claim:

The ornamental design for shorts or the like, as shown and described.

IRVING SMITH MARKS.
